UNITED STATES PATENT OFFICE

2,077,731

CHIMNEY SCRAPER

Albert J. Aaby, Rochester, Minn.

Application September 24, 1935, Serial No. 41,948

1 Claim. (Cl. 15—243)

This invention appertains to new and useful improvements in chimney cleaning means, and more particularly to a novel scraper which can be operated manually.

5 The principal object of the present invention is to provide a scraper which can be conveniently lowered into a chimney and expanded to the desired extent for effectively and efficiently scraping the inside of the chimney walls.

10 Various other important objects and advantages of the invention will become apparent to the reader of the following specification.

In the drawings—

15 Figure 1 represents an end elevational view of the scraper.

Figure 2 represents a side elevational view of the scraper.

Figure 3 represents a sectional view taken substantially on line 3—3 of Figure 1.

20 Figure 4 is a sectional view taken substantially on line 4—4 of Figure 1.

Figure 5 is a fragmentary detailed sectional view taken substantially on line 5—5 of Figure 2 showing certain parts removed.

25 Figure 6 is a cross sectional view taken substantially on line 6—6 of Figure 2.

Figure 7 represents a sectional view showing an arcuate shaped scraper desirable for use in round chimneys.

30 Figure 8 is an enlarged vertical sectional view on line 8—8 of Fig. 1.

Referring to the drawings, wherein like numerals designate like parts, it can be seen that the scraper unit consists in construction of an 35 elongated rectangular-shaped plate 5 provided with a pair of longitudinally extending flanges 6—6 at its edge portion.

40 Numeral 7 represents a vertically extending shell provided with side and bottom walls, said shell being provided with a pair of vertical slots 8 in opposite side walls thereof. The upper portion of the shell 7 is provided with a pair of laterally disposed extensions 9 which are secured as at 10 to the said top plate 5.

45 Pin member 11 extends through the end portion of the flanges 6—6 and also through the barrel-like formations 12 at the upper ends of the strip-carrying units. Each of these units consists of a pair of parallel strips 13—13 connected 50 together in definite spaced relation by a strap 14 at their upper ends, and by the scraping element 15 at their lower portions. The scraping element 15 may be only anchored on its length, as clearly shown in Figures 1 and 2.

55 As can be seen in Figure 4, a horizontal cross

bar 16 in the shell 7 is provided with pintles 17 at its ends for disposition through the slots 8 in the shell, and these pintles extend through the adjoining ends of links. Each pindle 17 extends through a pair of link members 18—18 for pivotally supporting the same and these links extend on to and are each pivotally connected to the corresponding lug end 19 of the saddle 20 which carries the corresponding pair of strips 13—13 on which the scrapers 15 are located.

Obviously, when this bar 16 is moved upwardly or downwardly in the shell 7, the scraper units are moved inwardly or outwardly to accommodate the device to various sized chimneys.

Vertically disposed through the shell 7 and 15 through the bearing 21 formed in the top plate 5 is the screw shaft 22 which at its lower end is provided with a pindle 23a extending through a small opening in the bottom of the shell 7, thus providing a cleat and a journal for the shaft. 20

Numeral 23 represents a stub which has a socket 24 therein for receiving the upper exterior end of the shaft 22 and the bolt 25 is disposed through this socket portion of the stub 23 for connecting the stub positively to the shaft 22.

25 Any number of pole sections 26 can be connected end to end by sleeves 27a, so that the scraper can be inserted into a chimney to any extent desired by employing the type of fastener shown clearly in Figures 1, 2, and 8. This fastener consists of a trough-like structure 27 pivotally secured to the section 26 through the sleeve 27a as at 28, this trough-like structure 27 being provided with grooved ears 29 into which the free ends of an elongated wire spring 30 can seat, 35 this spring being coiled around the pivot element 28 and having its spike disposed against the upper end of the sleeve 27a as in the manner shown in Figure 2, denoted by numeral 31. The free end of this trough-like structure 27 is provided with notches 32 for receiving studs 33 on the stub 23, these studs projecting through a sleeve 23' on said stub near the upper end thereof. 40

Obviously, by swinging this trough-like structure 27 outwardly, the section 26 can be disconnected from the stub 23.

45 Figure 7 discloses a slightly modified form of the invention wherein the scraper is denoted by reference character 15a, this scraper 15a being bolted or riveted as at 34 to the scraper 15 such 50 as is shown in Figure 2. In other words, to accommodate the device for a round interior chimney this arcuate shaped blade 15a can be applied to the straight type of scraper 15.

55 As can be seen clearly in Figures 1 and 2, a

substantially square plate 15a is located between the scraper element 15 and the strips 13 to serve as a brace for the scraping elements.

While the foregoing specification sets forth the invention in specific terms, it is to be understood that numerous changes in the shape, size and material may be resorted to without departing from the spirit and scope of the invention as claimed hereinafter.

Having thus described the invention, what is claimed as new is:—

A chimney scraper comprising a shell having slots in a pair of opposed sides thereof, a screw vertically disposed in the shell, operating means

attached to the upper end of the screw, a cross bar provided with pintles at the ends thereof slidably disposed in said slots, a cap on the shell through which said screw is journaled, said cap being elongated and extending beyond opposite sides of the shell, depending leg members pivotally connected at their upper ends to the end portions of the cap and having scraping members on the lower ends thereof, and links between the intermediate portions of said leg members and the pintles, said cross member provided with a threaded bore in which the screw is threaded.

ALBERT J. AABY.
